(57) **CLAIM**

We claim the ornamental design for a cocktail tray with stemmed glass holder, as shown and described.

DESCRIPTION

FIG. 1 is a perspective view showing the top and left side of the cocktail tray with stemmed glass holder.

FIG. 2 is a top plan view of FIG. 1;

FIG. 3 is a front elevational view of FIG. 1

FIG. 4 is a rear elevational view of FIG. 1

FIG. 5 is a right side elevational view of FIG. 1.

FIG. 6 is a left side elevational view of FIG. 1; and,

FIG. 7 is a bottom plan view of FIG. 1.
